UNITED STATES PATENT OFFICE.

RANDOLPH F. HALL, OF ITHACA, NEW YORK, ASSIGNOR OF ONE-FOURTH TO THEODORE P. HALL, OF WALLINGFORD, CONNECTICUT.

AIRPLANE.

Application filed October 8, 1924. Serial No. 742,400.

To all whom it may concern:

Be it known that I, RANDOLPH F. HALL, a citizen of the United States of America, and a resident of Ithaca, county of Tompkins, State of New York, have invented certain new and useful Improvements in Airplanes, of which the following is a specification.

This invention relates to certain improvements in airplanes; and the nature and objects of the invention will be readily recognized and understood by those skilled in the arts involved in the light of the following explanation and detailed description of the accompanying drawings illustrating what I at present consider to be the preferred embodiments or mechanical and aerodynamical expressions of the invention from among various other forms, arrangements, combinations and constructions of which the invention is capable within the spirit and scope thereof.

The invention relates particularly to that general class of air planes capable of vertical flight through the action of revolving airscrews or propellers directly or indirectly developing the requisite vertical lift for flight, and is more particularly directed to the arrangement and mounting of a plurality of such airscrews or propellers on an airplane of this type and to the solution of certain problems and the reduction of certain dangers encountered in the operation of a multi-propellered airplane of the vertical lift or flight type.

Where a plurality of propellers are employed for a vertical lift type of airplane, there are two general mounting arrangements which can be followed, either a tandem mounting of the propellers along the vertical axis of the airplane, or a mounting and disposition of the propellers laterally at opposite sides of the longitudinal axis of the airplane, as will be understood by those familiar with this art. The latter mounting is more efficient aerodynamically than the tandem mounting of the airscrews or propellers, but presents certain problems and results in certain inherent dangers in operation and use of an airplane having the propellers so disposed and mounted thereon. With the propellers mounted laterally at opposite sides of the longitudinal axis of

an airplane of the vertical lift or vertical flight type, a failure in the drive mechanism for the propeller or propellers, or a failure in a propeller itself; at one side of the airplane, will result in the establishment or creation of an unbalanced couple and destroy the desired flight condition and necessary equilibrium in flight essential to the proper operation and control of the airplane. Such loss of flight equilibrium in this type of airplane is a serious hazard and presents one of the problems and obstacles encountered with the use of the more efficient lateral mounting and disposition of airscrews or propellers on opposite sides of the longitudinal axis of the airplane to develop the vertical lift for flight thereof.

The present invention has as one of the main and fundamental objects thereof, a solution of the foregoing problem and the substantial elimination of the hazard and danger in flight with propellers mounted at opposite sides of the longitudinal or fore and aft axis of a vertical lift airplane, resulting from the failure of a propeller or the drive mechanism therefor, on one side of the airplane and the creation or establishment of an unbalanced couple.

Another object of the invention is the provision of an auxiliary or balanced drive mechanism for propellers of a vertical lift airplane which are mounted and disposed laterally at opposite sides of the longitudinal or fore and aft axis of the airplane, and which auxiliary drive will operate and cause substantially equal distribution of power to the propellers at both sides of the airplane upon failure of the main drive mechanism to a propeller at one side of the airplane.

A further object of the invention is the provision in an airplane of the vertical lift type having propellers disposed at opposite sides of the longitudinal axis of the airplane, for automatically rendering a propeller at one side of the airplane inoperative upon failure of a propeller at the opposite side of the airplane, in order to prevent the creation of an unbalanced couple and resulting loss of flight equilibrium.

A further object of the invention is to provide for automatically cutting off the power delivered to an airplane propeller upon failure of the propeller, so as to pre-

vent damage to the drive mechanism or power unit therefor, through continued operation of a broken propeller.

A further object of the invention is the provision of means controlled by the slip-stream of an airplane propeller for cutting off the ignition of the power unit driving the propeller and stopping the power, upon failure of the propeller or drive mechanism thereof.

Another object of the invention is to provide in an airplane of the vertical lift type having propellers mounted at opposite sides of the longitudinal axis thereof, a propeller drive mechanism which will cause continued operation of the propellers at both sides of the airplane upon failure of the drive mechanism to a propeller at one side, and to provide means for automatically rendering a propeller at one side of the airplane inoperative upon failure in a propeller at the other side thereof, so as to practically eliminate the possibility of creating an unbalanced couple and loss of equilibrium of the airplane in flight under any condition of failure in either the propeller drive mechanism or the propellers.

A further object of the invention is to provide certain improvements in design, construction and mounting of the mechanism and various elements forming the same, for carrying out the objects and securing the results of the invention, which will be efficient and positive in operation under the varying conditions encountered in use and operation.

With the foregoing general objects, and certain other objects and results in view which will be readily apparent to and understood by those skilled in the aeronautical art from the following explanation, the invention consists in certain novel features in construction and in combinations and arrangements of elements, as will be more fully and particularly referred to and specified hereinafter.

Referring to the accompanying drawings, in which similar reference characters refer to corresponding parts throughout.

Fig. 1, is a perspective view, more or less schematic or diagrammatical, of a vertical lift airplane having propellers mounted at opposite sides of the longitudinal axis and operated from a power unit through the medium of drive mechanism embodying the invention and having means of the invention for cutting off the power unit upon failure of a propeller, those elements of the propeller drive, power mechanism, and power control mechanism being shown in full lines, while the airplane is purely diagrammatically indicated in dotted outline.

Fig. 2, is a more or less diagrammatical view in side elevation of a type of vertical lift airplane in which the vertical lift is

indirectly developed from the propellers, with the various features of the invention embodied therein and applied thereto, parts of the airplane being shown in dotted outline.

Fig. 3, is a view of the automatic power plant cut-out switch of the invention, the casing therefor being shown in vertical section.

Fig. 4, is a view in longitudinal section through the slip-stream operated centrifugal switch of the invention, and showing the wind wheel driving member therefor.

Fig. 5, is a transverse section through the centrifugal switch taken on the line 5—5, of Fig. 4.

Fig. 6, is a detail fragmentary view of the centrifugal switch housing showing certain of the switch connecting posts.

Fig. 7, is a schematic view of the electrical connections between the power plant, and switches embodied in the invention.

Fig. 8, is a detail view in elevation showing the operative connections between one end of the auxiliary or balanced drive of the invention and one of the propellers of an airplane.

While the invention is primarily adapted to use with airplanes of the so-called vertical lift types, and in the examples of the invention disclosed herewith is presented as applied to and embodied in such types, there are certain features of the invention which are capable of general application to similar or equivalent airscrew or propeller mountings and arrangements and to the drive mechanism therefor on other types of aircraft. The mechanical and aerodynamical expressions of the invention illustrated and described herewith as applied to airplanes of the vertical lift types, are presented purely by way of example and not of limitation, because the problems and disadvantages overcome by the invention are encountered in a high degree with such types, and hence serve to more clearly bring out the principles and features of the invention and the results attained thereby.

In Fig. 1 of the accompanying drawings a vertical lift type of airplane is purely diagrammatically indicated in dotted outline to represent any desired design or type of airplane in which vertical lift is developed directly from the action of revolving airscrews or propellers, and embodies a body or fuselage 1 having control surfaces 2, and vanes or wings 3 all arranged and disposed in a more or less conventional manner to typify this general class of airplanes. A motor or power unit M is mounted on the body 1 at any desired point, in the present instance within the forward portion of the body in the usual manner, and airscrews or propellers P are mounted at opposite sides of the body above the vanes or wings.

3 and the body, and are spaced laterally at equidistant points from the longitudinal or fore and aft axis of the airplane. These airscrews or propellers P are rotated and 5 driven in a substantially horizontal plane from the motor M, to develop the requisite direct vertical lift for vertical flight of the airplane, as will be readily understood by those familiar with this type of airplane.

10 The propellers P are mounted on the vertically disposed propeller shafts 10 at opposite sides of the body 1 and extending upwardly from the vanes or wings 3. Shafts 10 are journaled at their lower ends in suitable bearings within the housings or casings 11, and are journaled at their upper ends in bearings 12' (see Fig. 8) within the housings 12, respectively, the propellers P being fixed in any suitable or desired manner 15 on the upper ends of the shafts 10 above housings 12 for rotation by these shafts. The bearings in lower housings 11 are similar to bearings 12' in housings 12. A system of bracing is provided between 20 the body of the airplane and the shafts 10 and housings in which mounted to maintain these shafts with the propellers P in rigid position and transmit the forces to which subjected to the airplane structure. In this 25 instance this system embodies an arrangement of brace and strut members 14 extending between the shaft housings 11 and 12 and the airplane structure, as will be clear by reference to Fig. 1 of the drawings 30 35 without requiring a detailed description thereof, any desired arrangement suitable to the particular type of airplane being employed.

The propeller shafts 10 are driven in any 40 suitable manner from the motor or power unit M, and in the example herewith an arrangement of shafting and gears is employed for transmitting the power from the motor to the propellers P and shafts 10. 45 A shaft 15 extends rearwardly from the motor M, either as an extension of the motor power or crank shaft or a separate shaft coupled thereto, and a transversely disposed shaft 16 is mounted extending between the lower ends of the propeller shafts 10. The power shaft 15 is operatively connected with the shaft 16 through the medium of worm gearing (not shown) within the gear casing 17, and the opposite ends 50 of the shaft 16 are provided with worm gears (not shown) within the gear casings 18, which casings are connected with and fixed to the housings 11 at the lower ends of the shafts 10, respectively. A worm gear 55 (not shown) is fixed on the lower end of each propeller shaft 10 within the housing 11 thereof, and is arranged in operative engagement with the gear in the casing 18 on the adjacent end of shaft 16, these engaged worm gears are formed to operatively

couple the opposite ends of shaft 16 with the propeller shafts 10 in such a manner as to rotate shafts 10 and propellers P thereon in opposite directions. With the foregoing arrangement of drive mechanism, the 70 propellers P are rotated or revolved in a substantially horizontal plane in opposite directions to develop the requisite vertical lift, by the motor M, through shafts 15 and 16 and the gearing operatively coupling the 75 same. The gearing is preferably of the worm type, although not so limited, and of usual conventional formation well known in the arts, so that it has not been deemed necessary to make a disclosure of such gears, 80 and particularly in view of a disclosure hereinafter of such gearing which is adapted for use in operatively connecting the propeller shafts 10, and shafts 15 and 16.

A vertical lift type of airplane embodying the foregoing general type of propeller mounting and arrangement and the drive mechanism therefor, is subject in flight to the possibility of failure in the drive mechanism to one of the propellers 10, in which event an unbalanced couple will be set up upon stoppage of the propeller at one side of the longitudinal axis of the airplane and the necessary equilibrium of the airplane destroyed with possible resulting loss of 95 flight control. According to the invention the above possibility with this type of airplane is eliminated by providing an auxiliary drive mechanism forming a balanced drive for and between the propellers P, so 100 that failure in one side of the main drive will not result in stoppage of the propeller connected therewith.

This auxiliary balanced drive embodies a shaft 20 extending between and operatively connected with the propeller shafts 10 at the upper or propeller ends thereof. Each propeller shaft 10, referring now to Fig. 8 in particular, is provided with a worm gear 21 fixed thereon within the bearing housing 12 between bearings 12' at the upper end of the shaft, and the adjacent end of auxiliary drive shaft 20 is provided with a worm gear or pinion 22 in operative engagement with the propeller shaft gear 21. A gear casing 23 is secured to, or formed as a part of, each housing 12, to enclose gear 22 in mesh with gear 21, on the adjacent end of shaft 20. Preferably a center bearing 24 is provided for the auxiliary or balanced drive shaft 20, and is suitably braced and supported from the body 1 by the brace members or struts 14 (see Fig. 1). The engaged sets of gears 21-22 operatively connecting the opposite ends of shaft 20 with the propeller shafts 10, respectively, are formed to rotate in opposite directions, that is to rotate the gears 21 on the shafts 10 in opposite directions so as to conform to the direction of rotation of the respective propeller shafts 10, as will be 130

readily understood. Gears similar to 21 and 22 can be employed for operatively connecting the ends of shaft 16 with shafts 10, and can be similarly arranged within the 5 housings 11.

In normal flight with the propellers P rotated by shafts 10 from the motor M, the shaft 20 is rotated by the shafts 10 and forms an auxiliary connecting drive mechanism therebetween. Now, if a failure occurs in flight to the drive mechanism for one of the propellers P while permitting the propeller on the opposite side of the airplane to operate, the auxiliary shaft 20 will 10 transmit power from the operating shaft 10 and rotate the propeller P at the opposite side of the airplane in the reverse direction, so that both propellers are rotated with an equal distribution of power therebetween 15 and the creation of an unbalanced couple through stoppage of a propeller on one side and continued operation of a propeller on the opposite side of the airplane is prevented. By the auxiliary balanced drive the 20 possibility of loss of equilibrium and control in flight through failure of the drive to one of the laterally mounted propellers is substantially eliminated. In the event of complete failure of the drive with stoppage 25 of both propellers, the condition referred to will not be present, and descent without power, according to the particular type of vertical lift airplanes can then be made.

Another failure condition is possible with 30 a propeller and drive mounting and arrangement of the foregoing general type, which will result in the creation of an unbalanced couple and loss of equilibrium in flight, namely, a failure in a propeller, *per se*, and 35 the invention provides for eliminating the results of such a failure by automatically cutting off the power driving the propellers, so as to prevent operation of a propeller on one side of the airplane with a propeller on 40 the opposite side of the airplane aerodynamically inoperative. According to one manner of carrying out this feature, the invention provides mechanism controlled by the 45 slipstream of each propeller for cutting off the ignition circuits, where an internal combustion motor power plant is utilized, upon 50 failure of a propeller, so as to stop the power and render the propellers on both sides of the airplane inoperative.

With the propellers mounted and arranged as shown in the instant example, and driven from a single motor or power unit, the mechanism for cutting off or grounding the motor ignition circuits includes switch 55 members 30 mounted in position to be acted upon and controlled independently by the slipstreams from the respective propellers P. Referring to Figs. 4 to 6 inclusive, of the accompanying drawings a design and 60 construction of centrifugal switch is shown

operated by a windwheel or screw, adapted for the purposes of this feature of the invention. The switch member 30 embodies a streamline hollow casing 31, of any suitable non-conducting material having one 70 end thereof open, and closed by a cap member 32 threaded into the end of the casing 31 and forming a support and bearing member for a shaft 33 which extends centrally therethrough and is journaled in a bearing 75 34 carried thereby. The shaft 33 extends longitudinally through the interior of casing 31 and is journaled in the reduced closed end portion thereof in a bearing 35. The reduced end of the casing 31 is provided 80 with a longitudinal bore therethrough axially aligned with shaft 33, and a carbon or other suitable conducting material contact plug 36 is disposed in this bore and maintained in engagement with the end of 85 shaft 33 by a coil spring 37 under compression between the outer end of the plug and an exterior cap 38 over the reduced end of casing 31 closing the bore therethrough. The cap 38 is provided with a screw 39 extending therethrough in contact with the 90 spring 37 for connection with an electrical conductor, such as a wire, cable or the like.

A contact ring 40 is mounted within the 95 casing 31 extending therearound at the reduced end thereof, adjacent the bearing 35 of the shaft 33, and is suitably fixed to the inner wall of the casing. A stud portion is formed extending from the ring 40 outwardly through the casing wall, and carries a screw forming a binding post 41 on the exterior of the casing for making electrical connection with the ring. A contact member embodying a pin 42 slidably mounted 100 in a bore formed transversely through the shaft 33 within the plane of or aligned with the contact ring 40, is provided for movement to and from electrical contact with the ring 40. A contact shoe 43 is fixed on one 105 end of the pin 42 for movement therewith to and from sliding electrical engagement with the contact ring 40, and a coil expansion spring 44 is mounted over pin 42 between shoe 43 and the shaft 33, normally 110 forcing the contact shoe 43 into engagement with ring 40. The opposite end of the pin 42 is provided with an enlarged cross head 45 of sufficient weight to be acted upon by centrifugal force upon rotation of shaft 115 33, as will be explained hereinafter.

The shaft 33 is extended a distance outwardly beyond the casing 31 and end cap 32, and a small windmill propeller or windwheel 46 is mounted thereon, in the usual 120 or any other desired manner, as by the retaining cap 47 threaded onto the outer end of the shaft. An annular ring 48 having a flange extending therefrom is mounted on the windwheel 46, with the flange extend- 125 130

ing over and around the exterior of the adjacent end of the casing to protect the casing and prevent entry of moisture or foreign matter into the casing. A loose, spacing washer 49 is mounted on shaft 33 between windwheel 46 and the casing end cap 32.

The operation of the switch member 30 is secured by rotation of the windwheel 46 and shaft 33, through the action of a stream of air upon the windwheel. Upon rotation of shaft 33 at a sufficient speed, dependent upon the strength of coil spring 43, the centrifugal force created acts upon weighted cross head 45 and causes it to move outwardly from shaft 33, which slides the pin 42 through the bore in the shaft and withdraws contact shoe 43, against the tension of spring 44, out of engagement with contact ring 40. When the speed of rotation of shaft 33 decreases below a predetermined rate, the spring 44 overcomes the decreased centrifugal force acting upon pin 42 and crosshead 45, and forces the contact shoe 43 outwardly into engagement with contact ring 40. The position of pin 42 and cross head 45, with contact shoe 43 out of engagement with ring 40, is indicated in dotted outline in Fig. 5 of the accompanying drawings, and the operation of the switch will be clearly understood by reference thereto.

In the example illustrated in Fig. 1 of the drawings, a switch member 30 is mounted in vertically disposed position below each of the propellers P, with the windwheel 46 thereof uppermost and located within the slipstream of the propeller P thereabove so as to be rotated thereby and cause the contact shoe 43, through shaft 33 and pin 42, to move out of engagement with ring 40. These slipstream actuated switch members 30, are electrically connected with and control a magnetic switch 50, or equivalent element, which is in turn connected in the magneto or ignition circuits of the motor M, so as to render the ignition circuits inoperative through operation thereof by switch members 30, under certain condition established by the propellers P.

The power plant or motor control member in the present instance is in the form of a magnetic switch, referring now to Fig. 3 of the drawings, connected in the magneto circuits of motor M, and includes a casing or housing 51, in the upper portion of which electro-magnets 52 and 53 are mounted disposed horizontally in longitudinal or axial alignment with the adjacent ends thereof spaced apart. Magnet 52 is electrically connected with binding posts 52^a and 52^b, and magnet 53 is electrically connected with binding posts 53^a and 53^b, all mounted on the upper side of casing 51 and accessible on the exterior of the casing. A contact arm 54 is pivotally mounted in vertically

disposed position intermediate the magnets 52 and 53, and extending upwardly therebetween for swinging movement or oscillation toward and from these magnets, respectively. The contact arm is pivoted intermediate the ends on a suitable pivot 55, and thus forms the upper contact arm 54 and the lower or depending contact arm 56. A pair of contacts 57 and 58 are mounted disposed at opposite sides, respectively, of the upper contact arm 54, and a similar pair of contacts 59 and 60, are disposed at opposite sides, respectively, of the lower contact arm 56. These contacts are so mounted and arranged with respect to the contact arm 54 that with the arm swung toward magnet 52 contact 57 is engaged and the lower arm 56 engages contact 60, while with upper arm 54 swung toward magnet 53, contact 58 is engaged thereby with lower arm 56 engaging contact 59. Spring catches 61 are secured to lower contacts 59 and 60, respectively, to engage the end of arm 56 and maintain the contact arm in either position swung toward magnet 52 or 53, and engaging the pairs of contacts 57-58, or 59-60, respectively. The catches 61 are formed with handles 62 depending therefrom outwardly through casing 51 and accessible on the exterior of the casing to permit springing open the catches to release the arm 56. The contact arms 54-56 are maintained in normal vertically disposed position with arm 56 midway between magnets 52 and 53, by a pair of coil springs 63 extending from opposite sides of the arm and secured at fixed points in the casing, so that upon release of the arm 54 from either position swung from the vertical, the spring 63 on the side opposite from the direction in which the arm is swung will draw or pull the arm back to normal position.

Exterior binding posts 57^a and 58^a are mounted at opposite sides of casing 51 on the under or lower wall thereof. Post 57^a is connected with the upper and lower contacts 57 and 59 by wires 63' and 64, respectively, and post 58^a is connected with the upper and lower contacts 58 and 60 by the wires 65 and 66, respectively. A single pole single throw knife switch 67 is mounted at one side of the casing 51, with one side thereof connected by wire 68 with exterior binding post 67^a mounted on the upper wall of casing 51, and with the other side thereof connected by wire 69 with the magnetic switch contact arms 54-56.

The motor M for driving the propellers P of Fig. 1, is of the double ignition type embodying two magnetos 70 connected with the usual cockpit switch S by wires 71 (see Fig. 7), all of the usual or other suitable types arranged in the conventional manner familiar in this art. In Fig. 7 of the accompanying drawings, the manner of elec-

trically connecting the ignition system of the motor M with the magnetic switch 50 and the slipstream controlled centrifugal switches 30, is purely diagrammatically disclosed. The magnetic switch 50 is suitably mounted in the body 1, or at any other desired point and is electrically connected with the ignition circuits of motor M through the switch S. Contact 71^a of switch 10 S is connected by wire 72 with binding post 57^a, and contact 71^b is connected by wire 73 with binding post 58^a, of the magnetic switch 50. Switch 50 is connected to ground G by wire 74 from binding post 67^a, and 15 switch S is connected to ground by wire 75 from contact 71^c to wire 74. Batteries B and B' are provided for energizing the electro-magnets 52 and 53, respectively, of switch 50, although any other desired source 20 of electrical energy may be employed for this purpose. One terminal of battery B is connected with one terminal of electro-magnet 52 by wire 76 through binding post 52^b of switch 50, and one terminal of battery B' is connected to one of the terminals 25 of electro-magnet 53 by wire 77 through binding post 53^a.

The centrifugal switches 30 are mounted, 30 as hereinbefore referred to, so as to be operated by the slipstreams from propellers P, respectively. These switches 30 are electrically connected in the circuits to the electro-magnets of magnetic switch 50 and control the operation of this switch. Contact 35 or binding post 41 of right hand switch 30 is connected by wire 78 with a terminal of battery B', and contact 39 of this switch 30 is connected by wire 79 with binding post 53^b for electro-magnet 53 of switch 50. The left hand centrifugal switch 30 is 40 connected from contact or binding post 41 thereof with a terminal of battery B by wire 80, and is connected with binding post 52^a for electro-magnet 52 by wire 81 from contact 39 thereof. In the wires 79 and 81 are placed switches 79' and 81', respectively, so that the circuits from batteries B and B', through centrifugal switches 30 to the electro-magnets 52 and 53, respectively, can be opened when the system is not 45 in use.

The operation of the foregoing system for 50 controlling and cutting off the power driving the airscrews or propellers of a vertical lift type of airplane, as in the example here-with, upon the establishment of certain propeller conditions in flight, is as follows. With the airplane not in use, the switches 79' and 81' are opened to open the battery 55 circuits to the electro-magnets of the magnetic switch 50. Preparatory to use or flight of the airplane, switches 79' and 81' are closed, and the centrifugal switches 30 are likewise closed, the contact shoes 43 thereof being in contact with rings 40, and

closed circuits from the batteries B and B' to electro-magnets 52 and 53 of magnetic switch 50 are established, as will be clear by reference to Fig. 7 of the drawings. These closed circuits energize electro-magnets 52 70 and 53, but as they are so designed as to exert an equal magnetic force, the contact arm 54 disposed vertically and midway therebetween, will have an equal force exerted thereon at opposite sides thereof and 75 will hence remain in normal inoperative position. The motor ignition switch S is then closed and motor M started and operated in the usual manner. Upon operation of motor M, the airscrews or propellers P are re-volved and result in rotation of centrifugal switches 30, through the action of the propeller slipstreams upon the switch wind-wheels 46 which lie within the slipstreams from propellers P, respectively. Rotation 80 of the shafts 33 of centrifugal switches 30 at the proper rate of speed, causes centrifugal force to slide the pins 42 through these shafts and withdraw contact shoes 43 from electrical engagement with the fixed contact 85 rings 40. Preferably, although not so limited, the springs 44 on pins 42, are of sufficient tension or strength to prevent withdrawal of shoes 43 from rings 40, until propellers P are rotated at a rate above the 90 usual rate at which idled in warming up the motor M. Further, it is desirable that the springs 44 be of as near the same strength and exert the same tension as practically 95 possible. Thus, when switches 30 are operated at the required rate of speed, the circuits from batteries B and B' to electro-magnets 52 and 53, are broken or opened and these magnets are deenergized. However, 100 due to the opposite springs 63 on contact arm 54, this arm is still maintained in normal vertical position midway between the magnets 52 and 53. In the foregoing manner by the arrangement of the system as 105 described, the magnetic switch 50 is maintained in normal inoperative condition with both propellers P either operating or not operating, as long as the condition of both propellers is the same.

With the airplane in flight, the centrifugal switches 30 are open, as previously explained, and electro-magnets 52 and 53 are deenergized, with contact arms 54—56 maintained in vertical inoperative position by the springs 63, of the magnetic switch 50. Now, assume that during flight a failure occurs in the right hand propeller P with the resulting cessation of the slipstream therefrom, or a decrease below a certain predetermined force, then rotation of the right hand centrifugal switch windwheel 46 stops or decreases below a predetermined point, and the centrifugal force acting upon pin 42 to maintain shoe 43 out of contact with ring 40 is removed, so that spring 44 si- 115 120 125 130 135

multaneously with such a condition, forces shoe 43 outwardly into electrical engagement with the contact ring 40 of this right hand switch 30. Engagement of shoe 43 with ring 40 of switch 30, closes the circuit from battery B' through wire 78, and contact 41, ring 40, shoe 43, pin 42, shaft 33, plug 36, spring 37, and contact 39 of the switch 30; wire 79 from switch contact 39 to the electro-magnet 53 of switch 50 through contact 53^b, and then from magnet 53 through contact 53^a, back to battery B' by wire 77 (see Figs. 7 and 8). Closure of the foregoing circuit by switch 30 energizes electro-magnet 53, and the left hand propeller P being operative, the left hand switch 30 maintains the circuit to electro-magnet 52 open and this magnet deenergized, so that energized magnet 53 magnetically attracts or draws the upper contact arm 54 of switch 50 toward the right and swings the same into engagement with contact 58 against the tension of left hand spring 63, and at the same time arm 56 is swung to the left, being below pivot 55, into engagement with contact 59. In this position contact arms 54—56 bridge and electrically connect the contacts 58 and 59, and are maintained in this position by the lower end of arm 56 snapping into the adjacent spring catch 61 which secures the contact arms against the tension of spring 63 into operative position. The electrical connection of contacts 58 and 59 results in short circulating or grounding the ignition circuits of motor M and stops operation of the motor. This is accomplished by closing and completing a circuit from the magnetos 70, through cockpit switch S and contacts 71^a and 71^b thereof, wires 72 and 73 to binding posts 57^a and 58^a and contacts 59 and 60, respectively, of the magnetic switch 50. The circuit is continued from contact 59 through contact arms 54—56 to ground G through wire 69, closed switch 67, wire 68 and binding post 67^a, and wire 74, and is continued from binding post 58^a by wire 65 to contact 58 and contact arm 54.

The operation of magnetic switch 50 by closing of the right hand centrifugal switch 30 upon failure of right hand propeller P, the slipstream of which controls switch 30, grounds the ignition circuits of motor M and stops operation of the motor and rotation of left hand propeller P. Thus, the establishment of an unbalanced couple due to stoppage of the right hand propeller and continued operation of the left hand propeller, of the laterally mounted propellers P, is prevented and the resulting possibility of loss of lateral equilibrium and flight control eliminated. A failure in the left hand propeller P will likewise result in stopping motor M, by closing left hand switch 30, through the circuits for grounding the motor in a manner similar to that described

with reference to a failure in the right hand propeller, and will be clear and understood by reference to Fig. 7 of the drawings. The loss of equilibrium in flight by failure in either of the laterally mounted propellers P is thus prevented by the foregoing system of the invention, and in connection with the hereinbefore described auxiliary or balanced drive for the propellers P, renders an airplane so equipped free of the inherent hazard or danger in flight occasioned by either a failure in a propeller per se, or in the drive mechanism thereto. The knife switch 67 provided for the motor control system is utilized to render the entire system inoperative, if desired, but is normally maintained closed, the switches 79' and 81' being used to temporarily render the system inoperative.

A different type of vertical lift airplane is purely diagrammatically disclosed in Fig. 2 of the drawings, with the auxiliary or balanced drive mechanism and the motor control system features of the invention applied thereto and embodied therein. In this type of vertical lift airplane, the laterally disposed propellers P are mounted on the propeller shafts 10, which latter are disposed at a forward inclination and angle to the vertical, and a wing cellule 3' is disposed rearwardly in the slipstream from propellers P, so as to be acted upon thereby and with the propellers P develop the requisite vertical lift in flight. This type may be aptly termed, and is here disclosed to exemplify, an air craft of the indirect vertical lift type, in which the vertical lift is indirectly derived and developed from rotating air screws or propellers. In the type shown in Fig. 2, the arrangement of propeller drive mechanism from motor M, including the balanced drive of the invention, is similar to that described with reference to Fig. 1, and the arrangement and operation of the control system for stopping the motor M upon failure of a propeller through the operation of the slipstream actuated switches 30 is likewise similar to that explained with reference to Fig. 1. The type of airplane shown by Fig. 2, is adapted not only for vertical flight but also for horizontal flight and for gliding flight in accordance with that of the conventional airplane. This is accomplished through the medium of the wing cellule 3', and a feature of the invention in cooperation with the drive mechanism and motor control system, resides in arranging the center of gravity 100 and gravity force vector 101 forward of the wing cellule vector 102, so that upon removal of the propeller thrust shown by vector 103, the flat plate resistance of the wing cellule 3' will produce a moment about the center of gravity which will place the airplane in a gliding attitude and also create a forward mo-

tion. Thus, upon operation of the motor control system of the invention to stop motor M and the propellers P driven thereby, propeller thrust force 103 is removed and the airplane automatically goes into and assumes a gliding attitude, which materially assists in the prevention of a loss of control.

In the examples of the invention disclosed and explained herein, a single power unit of 10 the internal combustion motor type is employed, but it is to be understood that the various features of the invention are not restricted to this type of power unit, or to the use of a single unit, as any desired number 15 of units may be employed, for instance an independent unit may be used for driving each airscrew or propeller employed.

With reference to that feature of the invention providing for the automatic cutting off or stopping of the power driving the propellers upon the development of certain propeller conditions in flight, attention is directed to the fact that the invention contemplates and includes other arrangements 25 and means for this purpose controlled by a propeller or propellers to stop the power driving the same, and by the present disclosure it is not intended to limit the invention to a centrifugal form of switch controlled by the slip-stream, or to the manner of stopping or rendering the power unit inoperative. If desired or found expedient, other means controlled from a propeller or the slipstream there- 30 of can be employed, as well as other methods of stopping or cutting off the power, than but cutting the ignition circuits of an internal combustion type of power unit, without stepping beyond the confines of the 35 broad principles exemplified by the present mechanical and aerodynamical expressions of this feature of the invention. Further, this feature of the invention is adaptable to aircraft generally, and can be applied to a power driven propeller to stop the power applied thereto upon failure in the propeller or drive, so as to prevent continued operation 40 of a propeller or the drive mechanism therefor after a failure therein and resulting damage from such continued operation, as will be readily recognized by those skilled in this art.

The examples of the invention illustrated 55 and described herewith disclose vertical lift types of airplanes embodying two laterally mounted propellers, but it is to be understood that the various features of the invention are applicable to aircraft employing any desired number and arrangement of 60 airscrews or propellers and can be embodied to function with all of such arrangements of multiple propellers or any number thereof.

It is also evident that various other forms, 65 arrangements, modifications and substitu-

tions might be resorted to without departing from the spirit and scope of my invention, and hence I do not wish to in any way limit myself to the exact and specific disclosures hereof.

Desiring to protect my invention in the broadest manner legally possible, what I claim is:

1. In aircraft, a plurality of propellers, a power plant, a main drive mechanism 75 from said power plant to each of said propellers, respectively and an auxiliary drive mechanism connecting the main drive mechanism to said propellers, said auxiliary drive operative to drive any one of said propellers upon failure in the respective main drive mechanism therefor.

2. In aircraft, a plurality of propellers, a main drive mechanism for each of said propellers, and an auxiliary drive mechanism 85 connecting and operated by said main drive mechanisms, said auxiliary drive operative to drive a propeller upon failure of the main drive therefor.

3. In aircraft, a plurality of propeller 90 shafts, propellers mounted on said shafts, and an auxiliary drive shaft connecting and operatively coupled to said propeller shafts adjacent the propellers mounted thereon, respectively, said auxiliary shaft operative to 95 drive anyone of said propellers upon failure of the shaft therefor, from the remaining propeller shafts with which connected.

4. In aircraft, a pair of propellers, separate main drive mechanism therefor, and an auxiliary drive mechanism extending 100 between, operatively coupled with, and driven by said main drive mechanisms.

5. In combination, propeller shafts, a 105 propeller on each of said shafts, a power unit for operating said shafts, and an auxiliary shaft operatively coupling said propeller shafts and driven thereby.

6. In combination, spaced, substantially 110 parallel driving shafts, propellers on each shaft adjacent one end thereof, a power unit operatively coupled with the opposite ends of said shafts for driving the same, and an auxiliary shaft operatively connecting and driven by said driving shafts adjacent said 115 propellers.

7. In combination, substantially parallel driving shafts having driven members at one end thereof and the power applied at the opposite ends thereof, and an auxiliary 120 drive shaft operatively connecting and driven by said driving shafts, intermediate the points of power application thereto and the members driven therefrom.

8. In an aircraft propeller drive, spaced 125 substantially parallel propeller shafts, propellers mounted on said shafts adjacent one end thereof, a power unit operatively coupled with said shafts adjacent the opposite ends thereof, and an auxiliary drive shaft 130

- extending between and operatively connect-
ed with said shafts adjacent the propellers
mounted thereon.
9. In an aircraft propeller drive embody-
ing spaced propeller shafts, propellers
driven therefrom, and a source of power for
operating said shafts and propellers, an
auxiliary balanced drive operatively con-
necting said propellers and driven from
said shafts, whereby failure in operation of
one of said propellers by the shaft and
power therefor will result in operation of
said propeller by said auxiliary balanced
drive and equal distribution of power to all
the propellers through the operative shaft
with which connected.
10. In an airplane, propellers mounted
laterally of the longitudinal axis thereof,
propeller shafts for said propellers, respec-
tively, drive mechanism for each shaft and
propeller, and an auxiliary drive extending
between, operatively coupled with and
driven by said propeller shafts, the said
auxiliary drive adapted to operate a pro-
peller upon failure of the drive mechanism
thereto, from an operative propelled shaft
with which coupled.
11. In an airplane, propellers mounted
thereon laterally of the longitudinal axis
thereof, drive mechanism for each propel-
ler, and an auxiliary drive operatively con-
necting said propellers and driven from and
by said propeller drive mechanisms, the said
auxiliary drive operating a propeller upon
failure of the drive mechanism thereof,
from an operative propeller drive mecha-
nism by which driven.
12. In an airplane, propellers mounted
thereon laterally of the longitudinal axis
thereof, spaced substantially parallel pro-
peller shafts for rotating said propellers,
respectively, a power unit, drive mechanism
from said power unit to said propeller
shafts, and an auxiliary drive shaft extend-
ing between and operatively connected with
and driven by said propeller shafts adjac-
ent the propellers rotated thereby.
13. In an airplane, propellers mounted
thereon laterally of the longitudinal axis
thereof, spaced approximately parallel pro-
peller shafts for rotating said propellers, a
drive mechanism for each propeller shaft
and propeller for rotating the same in oppo-
site directions, and an auxiliary drive shaft
extending between and operatively coupled
with said oppositely rotated propeller shafts
and driven thereby adjacent the propellers
operated by said shafts.
14. In an aircraft propeller drive, spaced
approximately parallel propeller shafts,
propellers mounted thereon for rotation
thereby, a power unit, drive mechanisms
connecting said power unit with said pro-
peller shafts for rotating the same with the
propellers thereon in opposite directions, a
gear on each propeller shaft adjacent the
propeller thereof, and an auxiliary drive
shaft extending between said propeller
shafts and provided with gears thereon op-
eratively coupling said shaft with the oppo-
sitely rotated propeller shafts and gears
thereof, respectively, whereby said auxiliary
shaft is driven from and by said propeller
shafts.
15. In aircraft, a propeller, a power plant
for driving the same, and means controlled
by the propeller slipstream for cutting off
the power driving said propeller upon fail-
ure of the propeller slipstream.
16. In aircraft, a propeller, a source of
power for driving said propeller, and means
controlled by said propeller for cutting off
the power delivered thereto upon failure of
the propeller.
17. In aircraft, a propeller, a source of
power driving said propeller, and means
controlled by the rate of speed at which said
propeller is driven for cutting off the power
driving the same when the propeller speed
drops below a predetermined rate.
18. In aircraft, a propeller, a source of
power for driving said propeller, and means
disposed within and controlled by the slip-
stream of said propeller for cutting off the
source of power driving the same when the
slipstream reaches a predetermined force.
19. In aircraft, a propeller, an internal
combustion motor driving said propeller,
and means controlled by the propeller for
cutting off the ignition circuits of said motor
under certain predetermined propeller con-
ditions.
20. In aircraft, a propeller, an internal
combustion motor, including the ignition
circuits therefor, driving said propeller, and
means controlled by the propeller slipstream
for cutting said ignition circuits to stop said
motor.
21. In aircraft, a propeller, an internal
combustion motor driving said propeller, the
said motor including ignition circuits, and
a cut-out switch therein, and means control-
led by said propeller slipstream for operating
said switch.
22. In aircraft, a propeller, an internal
combustion motor driving said propeller, the
said motor including ignition circuits hav-
ing a switch therein, and means controlled
by the propeller slipstream for operating
said switch, said means inoperative during
normal flight operation of said propeller
and rendered operative to cause said switch
to open the ignition circuits and stop said
motor upon decrease in the propeller slip-
stream below a predetermined force.
23. In aircraft, a plurality of propellers,
and means controlled by said propellers for
rendering all of them inoperative upon fail-
ure in operation of any one of them.
24. In aircraft, a plurality of power

driven propellers, and means controlled by each of said propellers for cutting off the power and rendering all of said propellers inoperative upon failure in operation of any 5 of the said propellers.

25. In aircraft, a plurality of propellers, a source of power for said propellers, and means controlled by each propeller for cutting off the power for all of said propellers 10 upon failure in operation of any of the said propellers.

26. In aircraft, a plurality of propellers, a source of power for driving said propellers, and means controlled by the slipstream 15 from each propeller for cutting off the power to stop operation of all of the propellers upon failure in operation of any of the said propellers.

27. In aircraft, a plurality of propellers, 20 a power plant of the internal combustion type for driving said propellers, a switch for grounding the ignition circuits of said power plant, and means controlled by the slipstream of each of said propellers for operating said switch to ground the ignition 25 circuits of said power plant and stop the operation of all of said propellers upon failure in operation of any of them and resulting substantial cessation of the slipstream 30 therefrom, respectively.

28. In aircraft, a plurality of propellers, an internal combustion motor for driving said propellers, an ignition system for said motor including electrical circuits therefor, 35 a switch connected in said circuits for grounding the same to render the motor inoperative, and means controlled by the slipstream of each of said propellers for operating said switch to ground the motor ignition 40 circuits upon failure of any one of said propellers and the slipstream thereof.

29. In an airplane of the vertical lift type, propellers disposed laterally of the horizontal axis of the airplane, a power plant for 45 driving said propellers, and means for rendering said power plant inoperative upon failure of one of said laterally disposed propellers.

30. In an airplane of the vertical lift type, 50 propellers disposed laterally of the horizontal axis of the airplane, a power plant for operating said propellers, and means disposed in and controlled by the slipstream from each propeller for rendering the power plant inoperative to stop the operation of 55 said propellers, the said slipstream controlled means operated to render the power plant inoperative by aerodynamic failure of the propeller and resulting substantial cessation of the slipstream therefrom.

31. In an airplane of the vertical lift type, propellers mounted laterally of the horizontal axis of the airplane, a power plant and drive mechanism for rotating said propellers, normally inoperative means for ren-

dering said power plant inoperative, and means disposed in and controlled by the slipstream of each propeller for actuating said means for rendering the power plant inoperative, said slipstream controlled means 70 operated to actuate said means and render the power plant inoperative by the failure of the slipstream controlling the same, respectively.

32. In a vertical lift type of airplane 75 capable of horizontal gliding flight, propellers mounted laterally of the longitudinal axis of the airplane, a power plant for rotating said propellers, and mechanism controlled by the slipstream from each propeller for rendering the power plant inoperative to stop rotation of said propellers upon failure of any one of said propellers, the airplane formed with the center of gravity 80 in relation to the other forces developed such that on stopping the rotation of said propellers the airplane automatically assumes horizontal gliding position.

33. In a vertical lift type of airplane 85 capable of vertical flight and of horizontal 90 flight, propellers mounted laterally of the longitudinal axis thereof, aerofoil surfaces mounted in the slipstream of said propellers and acted on thereby, a source of power for rotating said propellers, mechanism controlled by the slipstream from each propeller for cutting off the power to stop rotation of all of said propellers upon failure in operation of any one of the said propellers, and the center of gravity of the airplane 100 at a point forward of the force developed by the aerofoil surfaces, whereby upon cutting off of the power and stopping of said propellers, the airplane automatically assumes horizontal gliding position.

34. In aircraft, in combination, a propeller, and means controlled by the slipstream for rendering said propeller inoperative under certain predetermined propeller conditions.

35. In aircraft, in combination, a plurality of propellers, and means controlled by the slipstream for rendering all of said propellers inoperative under certain predetermined propeller conditions.

36. In an aircraft propeller drive, a power unit, propeller shafts disposed at opposite sides of said power unit, a drive shaft extending between and operatively coupled to corresponding ends of said propeller shafts, said power unit operatively connected with said drive shaft intermediate the propeller shafts, propellers mounted on the opposite free ends of the propeller shafts, and an auxiliary drive shaft extending between, 120 operatively coupled with and driven from and by said propeller shafts adjacent the propellers thereon, respectively.

37. In an aircraft propeller drive, a power unit, propeller shafts disposed at opposite 130

sides of the power unit, a drive shaft extending between corresponding ends of the propeller shaft, gearing operatively coupling the drive shaft with the ends of said propeller shafts, respectively, to rotate said propeller shafts in opposite directions, the power unit operatively connected with said drive shaft intermediate the propeller shafts, propellers mounted on the free ends of the propeller shafts, respectively, opposite the ends thereof coupled with said drive shaft, an auxiliary drive shaft extending between the propeller shafts adjacent the propellers thereon, and gearing operatively coupling said auxiliary drive shaft with the oppositely rotated propeller shafts, respectively, said auxiliary drive shaft driven from and by the said propeller shafts.

38. In an airplane including a body and

a power unit mounted within the body, a 20 propeller drive embodying propeller shafts disposed at opposite sides of said body, a drive shaft extending transversely of the body and operatively coupled to corresponding ends of said propeller shafts, a power 25 shaft from the power unit to said drive shaft operatively coupled therewith intermediate the propeller shafts, propellers mounted on the ends of said propeller shafts opposite the coupling of said shafts with the drive shaft, and an auxiliary drive shaft extending between and operatively coupled with said propeller shafts adjacent the propellers thereon, the said auxiliary drive shaft 30 operated by said propeller shafts. 35

Signed at Ithaca, New York, this 4th day of Oct. 1924.

RANDOLPH F. HALL.
